UNITED STATES PATENT OFFICE.

JAMES C. COVERT, OF WATERVLIET, NEW YORK, ASSIGNOR TO COVERT MANUFACTURING COMPANY, OF WATERVLIET, NEW YORK, A CORPORATION OF NEW YORK.

BREAST-STRAP SNAP-HOOK.

No. 908,843.

Specification of Letters Patent.

Patented Jan. 5, 1909.

Application filed November 6, 1907. Serial No. 400,932.

To all whom it may concern:

Be it known that I, JAMES C. COVERT, a citizen of the United States, residing at Watervliet, in the county of Albany and State of New York, have invented certain new and useful Improvements in Breast-Strap Snap-Hooks, of which the following is a specification, reference being had therein to the accompanying drawing.

10 This invention relates to an improvement in breast strap snap hooks and it is embodied in the construction and arrangement of parts presently to be described and defined in the claims.

15 While the invention is particularly designed and intended for the purpose as above indicated, it is to be understood that it may be used in other connections and still come within the scope of the invention.

20 Heretofore in this class of devices, it has been customary to secure on the side of the hook part a clip or clevis member to which the martingale is attached. This has been objectionable in that it required the application 25 of a fixture, namely, the link or clip of the martingale being permanently attached to the hook and further it destroyed the balance of the hook and required a special construction of hook to adapt the invention 30 to the use intended.

My invention is designed to provide a snap hook for breast straps, or what is known as the "roller snap," with a frame projection in the form of a closed loop located immediately 35 in the rear of the roller and conveniently to arrange a loop of that character on opposite sides of the frame so that the hook can be used as a right or left hook.

While I have shown in the accompanying 40 drawings a form of roller snap for breast straps, I desire it understood that the form illustrated is preferred but that the invention is not necessarily limited to the details of the construction shown.

45 In the drawings, Figure 1 represents in perspective a roller breast strap hook showing a snap hook for the martingale strap attached thereto, Fig. 2 is a plan view of the frame part slightly modified in that it omits 50 the hook part.

A designates the snap hook, B the U-shaped frame having in the outer end of its two branches alined perforations or openings through which passes the pintle C carrying 55 the anti-friction roller D. The frame part

between the roller and the hook is somewhat elongated, that is to say, the arms are lengthened to an extent greater than has heretofore been used and on the outside of the said arms between the pintle and the end bar of the 60 frame are secured conveniently integrally the U-shaped frames or closed loops F. I have shown a loop F on opposite sides so that the hook can be utilized as a right or left hand breast strap snap hook. 65

G designates the snap attached to the martingale strap shown in dotted lines. The snap proper is of a construction well known so that in use it can be readily snapped into the closed loop or frame on the breast strap 70 hook and removed therefrom as occasion may require it. Incidentally, by constructing the closed loops of the breast strap snap so that they will receive an ordinary snap hook, the latter is rendered removable easily so 75 that it can be taken from the breast strap snap and clip into the hames ring of the harness when desired. The capability of connecting the martingale to the closed loop or frame on the U-shaped frame of the breast 80 strap snap hook is highly advantageous. By the construction of U-shaped frame with its closed loops located in the position shown, a very rigid construction is provided, one that can be readily cast and that requires no ad- 85 justments or the application of any auxiliary devices for retaining the parts in place after connection with the martingale strap. A further advantage in locating the loops as shown is that they are located beyond the 90 ends of the pintle of the roller and do not interfere with the proper heading up of the pintle.

In Fig. 2, I have shown the construction somewhat similar to that of Fig. 1, differing 95 only in the shape of the loops and omitting the hook, appreciating in this connection that other attaching devices may be used instead of the integral hook, as shown in Fig. 1. A further advantage of the construction 100 shown is that the loops are so positioned as to constitute a perfect finish to the entire construction, the forward side of the loop portion forming conveniently a continuation of the end bar of the U-shaped frame, all pins and objectionable projections being thereby avoided. A further object is that in casting the U frame, it is easy to form the closed loop in that they are located on the outside of the frame and in the plane thereof. 105 110

Having thus described the invention, what is claimed as new and desired to be secured by Letters Patent is:

1. In a breast strap device, a substantially **U**-shaped frame, a hook extending from said frame and adapted to lie in a plane at right angles to the plane of the frame, a breast strap supporting roller supported in the ends of said frame, and a longitudinally disposed closed snap receiving loop on one of the arms of said frame, one of the arms of said loop being connected to said **U**-shaped frame in rear of the roller and the other arm of said loop frame being connected to said **U**-shaped frame and in alinement with the back bar thereof.
2. A breast strap snap device, a substantially **U**-shaped frame, breast strap support-

ing means connecting the ends of the arms of said frame, and oppositely arranged closed loops formed on the respective arms of the frame and extending longitudinally thereof. 20

3. In a breast strap attaching means, the combination with a frame having a hook extension and an anti-friction roller, of two oppositely arranged closed loops formed on the respective arms of the frame intermediate the plane of the roller and attaching device, said loops extending longitudinally of the arms of the frame. 25 30

In testimony whereof I affix my signature in presence of two witnesses.

JAMES C. COVERT.
